UNITED STATES PATENT OFFICE.

WILLIE MANOAH SEVERANCE, OF LAUDERDALE, MISSISSIPPI.

GARMENT-HANGER.

1,258,476.

Specification of Letters Patent.

Patented Mar. 5, 1918.

Application filed July 18, 1917. Serial No. 181,363.

To all whom it may concern:

Be it known that I, WILLIE MANOAH SEVERANCE, a citizen of the United States, residing at Lauderdale, in the county of Lauderdale and State of Mississippi, have invented new and useful Improvements in Garment-Hangers, of which the following is a specification.

The present invention relates to garment hangers, referring more particularly to the collapsible type primarily adapted for supporting pants, skirts, ties or the like articles of wearing apparel, and so constructed to adapt the garment hanger when not in use 15 to be folded into compact form, thus occupying but a minimum amount of space in storing the same in a dress suitcase, trunk or the like place.

The invention furthermore among other 20 features contemplates the production of a hanger formed of wire and constitutes a plurality of frames hingedly connected to one another, and a supporting loop carried by one of said frames which facilitates in not 25 only suspending the frame on a suitable support, but may be utilized as a clamp for clamping the frames in a folded or compact position.

With the above and other objects in view, 30 the invention consists in the novel features, details of construction and combination of parts which will hereinafter be more fully set forth, illustrated in the accompanying drawing and pointed out in the appended 35 claims.

Figure 1 is a perspective view of the hanger in open position; and

Fig. 2 is a plan view showing the same in folded locked position.

Referring more particularly to the accompanying drawing, in which like characters of reference refer to corresponding parts in the several views, the hanger generally is 40 denoted by the character 5 and shown as 45 constructed solely of wire, and embodying a main supporting frame 6, a lower supporting frame 7, the lower supporting frame being connected with the upper supporting frame through the medium of an intermediate 50 supporting frame 8.

The main upper frame of the hanger is 55 constructed from a single strand of wire bent to provide a substantially inverted U-shaped bearing 9, the legs 10 of the bearing being bent in an opposite lateral direction to provide a pair of outwardly and down-

wardly curved arms 11, and said arms being connected together through the medium of a U-shaped connecting bar 12. The horizontal portion of the connecting bar has suspended therefrom the intermediate frame 8, and this frame is of substantially U-shaped form and likewise constructed of a single strand of wire, forming the frame with spaced parallel limbs 13 and a horizontal 60 connecting portion 14. Each of the limbs 13 of the intermediate frame is terminally bent to provide bearing eyes 15 in which the connecting bar of the main supporting frame is journaled and consequently hing- 65 edly connects the intermediate frame with the main supporting frame. Furthermore, the limbs 13 of the intermediate frame are of a resilient character and tend to friction- 70 ally engage with the vertical side portions 16 of the connecting bar for preventing any accidental swinging or loose movement of the intermediate frame with respect to the main upper supporting frame. The lower frame 7 is constructed of a single strand of 75 wire and bent to provide the same of U-form, presenting spaced limbs 17 connected to one another through the employment of the horizontal connecting bar 18. Bearing eyes 19 are provided on the terminals of the limbs 80 17 and through which the connecting portion 14 of the intermediate frame is journaled, serving to hingedly connect the lower frame on the intermediate frame.

As far as the description of the invention 90 has been proceeded with, I am desirous of stating that the main upper supporting frame is generally intended for supporting coats or the like, whereas trousers are adapt- 95 ed to be supported on the U-shaped connect- 100 ing bar 12 thereof, while the respective connecting bars of the intermediate and lower frame, are primarily intended to support shirts, ties or the like articles of wearing apparel.

Pivotedly connected on the horizontal portion of the U-shaped bearing 9 is a supporting loop 20 capable, when the hanger is in an unfolded form, to support the same on a suitable support such as a nail or the like. 105 21 designates a second bearing of U-shaped form constructed from a single strand of wire having the terminals of its limbs 22 looped around the inner ends of the opposite curved arms 11 and at a point adjacent the 110 point of connection of the bearing 21 with the supporting arms, the limbs are further

coiled to provide a pair of aligned transverse bearings 23. A garment hook 24 is pivotally mounted on the horizontal portion of the second bearing 21 for a vertical swinging movement. This garment hook is adapted for a vertical swinging movement and of a length whereby when the same is swung to a folded position, the same will contact with the connecting portion of the bearing 9 and 5 limit the inward upward movement of the same. A brace 25 of substantially U-form has its limbs terminally provided with trunnions 26, and adapted upon the contact of the convexed portions 27 of the spaced 10 parallel strands of the garment hook, to automatically swing the brace in an outward direction until the concaved portions 28 of the garment hook receive the connecting portion of said brace. 15

20 From the foregoing description, taken in connection with the accompanying drawing, the advantages of construction and the method of operation will be readily apparent to those skilled in the art to which the invention relates, and while I have described the principles of operation of the invention, together with the device which I now consider to be the best embodiment thereof, I desire to have it understood that the device 25 shown is merely illustrative, and that such changes may be made when desired as are 30 within the scope of the appended claims.

What is claimed as new, is:—

1. A garment hanger comprising a main 35 supporting frame, an intermediate supporting frame and a lower supporting frame hingedly connected to one another, a bearing formed on one of said frames, a second bearing connected below the first mentioned 40 bearing, a supporting loop pivotally connected with the first mentioned bearing, the

said first mentioned bearing serving to limit the movement of the garment supporting hook in one direction.

2. A garment hanger comprising a main 45 supporting frame, an intermediate supporting frame and a lower supporting frame hingedly connected to one another, a bearing formed on one of said frames, a second bearing connected below the first mentioned 50 bearing, a supporting loop pivotally connected with the first mentioned bearing, the said first mentioned bearing serving to limit the movement of the garment supporting hook in one direction, a brace journaled in the second mentioned bearing and 55 operated to an open position upon the swinging movement of the supporting hook in an outward direction.

3. A garment hanger embodying a main 60 supporting frame, said supporting frame being constructed from a single strand of wire and bent to provide an inverted U-shaped bearing, a second bearing connected with the main supporting frame and provided with spaced bearing eyes, a brace pivotally supported in the eyes of the second mentioned bearing, a supporting hook pivotally connected on the horizontal portion of the second mentioned bearing for vertical 65 swinging movement and of a length to terminally engage with the connecting portion of the first mentioned bearing when in a folded position, said supporting hook being provided with convexed portions, the 70 convexed portions of the supporting hook operatively moving the brace in an outward direction and holding the hook in supporting position.

In testimony whereof I affix my signature. 75

WILLIE MANOA SEVERANCE.
